UNITED STATES PATENT OFFICE.

LYMAN W. SUTTON, JR., OF NEWTON, N. J., ASSIGNOR OF FOUR-FIFTHS OF HIS RIGHT TO FANNIE L. MATTISON, WM. M. SMITH, AND CHAS. A. SMITH, OF SAME PLACE, AND WILLIAM McMURTRIE, OF WASHINGTON, D. C.

TRANSMITTING-TELEPHONE.

SPECIFICATION forming part of Letters Patent No. 229,489, dated June 29, 1880.

Application filed March 31, 1880. (No model.)

To all whom it may concern:

Be it known that I, LYMAN W. SUTTON, Jr., a citizen of the United States, residing at Newton, in the county of Sussex and the State of New Jersey, have invented a new and useful Improvement in Transmitting - Telephones; and I do hereby declare the following to be a full, clear, and exact description of the invention, reference being had to the accompanying drawing, and the letters of reference marked thereon, which forms a part of this specification.

My invention relates to that portion of transmitting-telephones which effects and completes the transfer and transformation of the undulations produced by sound to corresponding undulations in the electric or voltaic current passing through the instrument, and has for its object to simplify the construction and increase the durability of the instrument and its effectiveness in operation.

To attain this object I make use of the combination and construction illustrated in the drawing hereinbefore mentioned, in which A is a plate, of wood or other suitable substance, having a perforation, B, made trumpet-shaped to concentrate the waves of sound that must pass through it to the metallic diaphragm X prepared to receive them, placed immediately behind it, and held in place against a suitable shoulder by a second plate of wood or other suitable substance, E, attached to the plate A by means of the screws I I. Both plates are chambered to give place to and secure the diaphragm and other parts. To the center of the back of the diaphragm X, and directly opposite to the center of the trumpet-shaped opening or mouth-piece B, is attached a small block of gas-retort carbon, C. Directly opposite to this carbon, and in the back plate, E, is a cylindrical perforation, forming a collar, of proper caliber to admit of the free passage and motion without friction of a metallic plunger, D, with pointed platinum tips attached to each

end of it and introduced within the said perforation. Outside the back plate, E, and directly opposite to the perforation and the plunger D, is a second block of gas-retort carbon attached to a strong metallic adjustment-bar, F, which serves to effect the proper contact of the plunger and the two carbon blocks, and which is operated from the front by means of the set or adjustment screw G. The platinum-tipped metallic plunger acts as a connection between the two carbons. The wires H H, attached, respectively, to the metallic diaphragm X and the adjustment-bar F, serve to complete the current from the battery through the several parts of the instrument. The freedom of back-and-forward motion thus provided for, the platinum-tipped plunger reduces the resistance to the vibration produced by the impact of sound-waves upon the diaphragm X, and thus favors increased distinctness of the undulation in the conveying current and consequently in the articulations of the receiving instrument. The platinum tips remove the possibility of derangement of this portion of the instrument by oxidation and destruction of the electrical contact with the carbons.

The special form and substance of the inclosing-case are not particularly material to my invention, and may be modified as desired.

What I claim as my invention, and desire to secure by Letters Patent, is—

The platinum-tipped plunger D, acting between and in connection with the carbons c c to secure a maximum simplicity and cheapness of construction, durability, and perfection in transmission of articulations.

In testimony whereof I have hereunto set my hand this 26th day of March, 1880.
